(57) **CLAIM**

The ornamental design for a multimedia vehicle, as shown and described.

DESCRIPTION

FIG. 1 is a front, top, left perspective view of a multimedia vehicle, showing our new design;

FIG. 2 is a back, top, left perspective view of the multimedia vehicle shown in FIG. 1;

FIG. 3 is a back, top, right perspective view of the multimedia vehicle shown in FIG. 1;

FIG. 4 is a front, top, right perspective view of the multimedia vehicle shown in FIG. 1;

FIG. 5 is a front view of the multimedia vehicle shown in FIG. 1;

FIG. 6 is a back view of the multimedia vehicle shown in FIG. 1;

FIG. 7 is a left side view of the multimedia vehicle shown in FIG. 1;

FIG. 8 is a right side view of the multimedia vehicle shown in FIG. 1; and,

FIG. 9 is a top view of the multimedia vehicle shown in FIG. 1.

The broken lines are included for the purpose of illustrating portions of the multimedia vehicle and form no part of the claimed design.

The multimedia vehicle shown in FIGS. 1-9 are from a perspective of edges of inside walls of the multimedia vehicle, where a portion of an inner and outer wall is cutaway.

1 Claim, 9 Drawing Sheets(56)
